UNITED STATES PATENT OFFICE.

ARENT AUGESTAD, OF MARKA BRANDBU STATION, HADELAND, NORWAY.

INLAY-SOLE FOR THE PREVENTION OF THE DEVELOPMENT OF GALLS.

1,352,865.

Specification of Letters Patent. Patented Sept. 14, 1920.

Application filed July 8, 1919. Serial No. 309,368.

To all whom it may concern:

Be it known that I, ARENT AUGESTAD, citizen of Norway, residing at Marka Brandbu Station, Hadeland, Norway, have 5 invented new and useful Improvements in Inlay-Soles for the Prevention of the Development of Galls, of which the following is a specification.

The present invention relates to improvements in inlay soles for boots or shoes, the object of the invention being to provide a device of this character which will prevent the chafing of the feet of the wearer and thereby avoid the formation of galls or 15 blisters.

The drawing accompanying and forming part of this specification illustrates in side elevation, partly in section, an embodiment of the invention.

20 It stands to reason that boots which are manufactured wholesale very seldom fit the foot so exactly that when the wearer is walking they can follow the movements of the foot with accuracy. This is especially 25 the case when heavy laced boots such as are used by workmen and soldiers are worn. With such boots it is impossible to prevent the foot—under its efforts to bend the sole and the boot—from moving to a certain extent 30 within the boot or shoe, the result of which movement is that the heel of the foot rubs against the heel of the boot, thereby causing the formation of blisters.

The object of the present invention is to 35 provide a device by means of which the inevitable movement of the foot with relation to the boot shall not produce any injury or discomfort to the wearer. This is accomplished by fixing the position of the foot 40 within the boot so that a predetermined distance is maintained between the heel and toe of the foot and the heel and toe of the boot, whereby the foot may move within the boot without chafing. To obtain this result a 45 suitable intermediate part is placed between the foot and the boot, consisting of a double inlay sole, one part of which is adapted exactly to fit the bottom of the boot or shoe and the other part of which comprises means 50 for securing it to the foot and preferably has the form of a heel-cap with fastening belts or laces.

Referring to the drawing, 1 is the lower by-sole, which is made of a stiff material 55 such for instance as zinc or hard, stiff

leather. To the toe part of this sole the flexible sole 2 is fastened. The connecting seam 3 is situated at a predetermined distance from the tip of the sole in order to render the cutting of the edge possible, 60 which is necessary in order to adjust the by-sole exactly to the bottom of the shoe. In order to make it possible during walking to move the sole 2 freely with relation to the by-sole, the latter extends somewhat beyond 65 the rear end of the sole 2. Adjacent to the rear end of the sole 2 is secured a heel cap 4 of suitable height to give the necessary support to the foot during walking. This heel cap is provided with lengthened side portions 5 which embrace the foot and may be connected to each other by means of strings or laces 6 over the ankle. 70

It will be understood that the by-sole when correctly cut will lie immovable in the 75 boot just as if it was fastened to the bottom of such boot or shoe, although it may be taken out and inserted into another shoe of suitable length. If, for instance, the length of the foot is 26 centimeters the by-sole 80 should have a length of approximately 30 centimeters and should extend 3 centimeters to the front of and 1 centimeter to the rear of the foot. The sole will then fit into a shoe of the proper size for such a foot. 85

In the use of a device such as above described the foot will occupy a fixed position with relation to the shoe, so that neither toe nor heel will come into contact with it, whereby the formation of blisters is prevented while at the same time the natural 90 mobility of the foot is maintained.

The foot may, of course, move inside of the shoe by reason of its anatomical natural joint connections without the use of an intermediate part between the foot and the shoe as above described, but this mobility is combined with chafing and unnecessary straining of the foot, whereas by the use of this improved device the foot retains its free mobility without being subject to such straining or chafing, since it effects the bending of only the flexible sole which is connected to the foot, the by-sole and the shoe not following the movements of the foot. This involves also an easier walk than without the inlay device described. 100

It is evident that the details of construction of the inlay device may be varied without departing from the spirit and scope of 110

the present invention. For instance, the flexible sole may comprise means for the connection between the foot and the heel cap described and shown.

5 Having thus described my invention, what I claim is:

1. An inlay device for shoes, comprising a flexible sole, a comparatively rigid sole connected to said flexible sole at the toe tip of 10 the latter, and means for fastening said flexible sole to the foot of the wearer.

2. An inlay device as set forth in claim 1, the flexible sole being provided with a heel cap.

15 3. An inlay device as set forth in claim 2, the heel cap being provided with elongated side parts adapted to be connected together over the ankle of the wearer.

4. An inlay device as set forth in claim 1, 20 the flexible sole being connected to the rigid

sole at a predetermined distance from the toe tip of the latter.

5. An inlay device as set forth in claim 1, the heel portion of the rigid sole extending behind the heel portion of the flexible sole. 25

6. An inlay device as set forth in claim 1, the rigid sole extending beyond the flexible sole at both ends thereof.

7. An inlay device as set forth in claim 1, the flexible sole being provided with a heel 30 cap having elongated side portions adapted to be connected together over the ankle of the wearer and the rigid sole extending beyond the flexible sole at both ends thereof.

In testimony whereof I have signed my 35 name to this specification.

ARENTE AUGESTAD.
